UNITED STATES PATENT OFFICE.

ANSON SEARLS, OF NEWARK, NEW JERSEY; LUCY A. SEARLS EXECUTRIX OF SAID ANSON SEARLS, DECEASED.

JACK.

No. 891,959.

Specification of Letters Patent. Patented June 30, 1908.

Application filed July 1, 1904, Serial No. 214,870. Renewed November 2, 1907. Serial No. 400,379.

To all whom it may concern:

Be it known that I, ANSON SEARLS, a citizen of the United States of America, residing at Newark, in the county of Essex and State 5 of New Jersey, have invented certain new and useful Improvements in Jacks, of which the following is a specification, reference being had to the accompanying drawings, forming part of the same, in which—

10 Figure 1 is a side elevation of a jack embodying my invention; Fig. 2, is a side elevation of the rack proper, of such jack; Fig. 3, is a side elevation of the extension or telescopic section; Fig. 4, is a sectional view of 15 the rack, showing the lugs for holding the extension; Fig. 5 is a sectional view of the extension section; and Figs. 6 and 7, are sectional views of the rack and the telescopic section, Fig. 7 showing them arranged as they 20 are when the section is partially extended, and Fig. 6 showing them shut closely together.

My invention relates to lifting jacks and consists in the combination with the rack, 25 of a telescopic section, arranged to be inclosed within and slide up and down in the rack section, so that the range of usefulness of the jack may be greatly extended, without increasing the parts or the weight any considerable number or amount.

The form of jack with which I show the invention is one I have devised, adapted to fold into small compass, and fully described and shown in my U. S. Letters Patent No. 35 782421 issued Feb. 14, 1905.

It consists among other parts of a rack R, supported in a head H, which in turn is supported on legs L L'. The rack operated by pawls or hooks P, P', and an arm or lever 40 A, the rack being lifted or lowered by a step by step movement, one pawl secured to the lever A, and successively taking into the teeth of the rack to lift or lower the load, and the other pawl secured to the head H, also 45 taking successively into the teeth of the rack and holding the load while the lever is operated to shift the first pawl from one tooth of said rack to another. But it is desirable that such a jack be susceptible of carrying 50 or storing in a limited space, and that necessarily limits the range of a jack that has only a simple head and legs and rack. The limit of its range can not be more than, indeed can not be quite, double that of its shortest condition. Thus, if one is constructed

to take under an axle not over $10\frac{1}{2}$ inches high, as required for the average light automobile car, then it could not well operate one much over 18 inches high, on the heavier class of motor cars, and as it is sometimes desirable to lift an automobile with a high wheel, or a carriage whose axle is more than 18 inches from the ground, the jack above described would be unequal to the task and a larger one would be needed, 60 but a larger one takes up too much space. I have therefore devised one in which the rack is hollow (or in the form of a hollow U shaped trough) and I have constructed another, or telescopic section, adapted to fit in 65 said trough, and to lie substantially wholly inclosed therein, when a low axle is to be raised, or the device is to be stored in the tool box, and yet susceptible of extension therein to almost its full length, when that is desired, 70 and I have so formed it that the parts are nevertheless capable of folding into a very small compass when not in use. Much study 75 and experiment has been required to provide parts which would be thus operative and yet 80 furnish the strength required of jacks in the severe service to which these are subjected. First, I form the rack in the form of a hollow trough with sides and bottom, or front, the front being preferably constructed so as to 85 constitute rungs, bars or steps into which the hooks may take. Then I form lugs, preferably two, l^4 , l^5 , on the rear of the bottom (or front) wall of the rack projecting upward, and a third l^6 , projecting from a brace b, which 90 extends across from one side of the rack to the other, at the top. Then I form a telescopic section T, also (preferably) in the form of a hollow trough, corresponding in shape to 95 the rack, and provided with a head h, and with apertures a, adapted to receive the lugs l^4 , l^5 , the bottom of the head h, and the top of the rack being shaped to conform, one to the other, when the extension is down, at 100 which time lug l^6 will take under and assist in supporting the head h, of the part T. Now I slide the section T into the rack portion R, and then, swinging the lower end out of the trough of rack R, I preferably drive a pin p^4 105 through the walls of the part T, the result of which is that the rack cannot be lost out of its place, for the pin p^4 will contact with lug l^6 when the extension is drawn nearly out and will prevent further movement in that 110 direction. The head h, is preferably given a

generally concave form with scallops, as shown, to insure its taking and holding under any axle or clip upon the body that it may be desired to lift.

- 5 The operation is manifest. If the jack is set up and the body to be raised is low, the rack and section T are left in the position shown in Fig. 6 and the lifting is done substantially as though there were no telescopic section. If the body to be raised, (for instance, the axle of a carriage) is higher than the range of the jack and rack R, then it is only necessary upon setting up the jack to pull up the section T, till it nearly reaches the desired height or (preferably) a little more than the distance from the top of the rack, when extended, to the axle; to then seat section T on the lugs $\frac{1}{4}$, $\frac{5}{8}$, by passing them into aperture a, to then place the thus extended jack (in the position of Fig. 1 for instance) under the axle and operate the lever A, to further raise the jack and section T and lift the vehicle. I have thereby produced a jack which, though it may be shut into a space 12 inches by 3 by $2\frac{3}{4}$, or less may also be readily extended so as to lift axles or other bodies ranging from the axle of a heavy wheel (with collapsed tire) whose diameter is 28 inches to one of a horse drawn carriage whose diameter is 50 inches, (the highest horse drawn carriage wheels), and that too without adding but one part, and only about $2\frac{1}{3}$, per cent. to the weight, of the jack.

35 What I claim as my invention and desire to secure by Letters Patent is,

1. A lifting jack provided with a hollow rack and a telescopic extension inclosed therein, each of said parts being provided with engaging devices arranged to take one into the other and to hold the parts in an extended position, combined with means for

lifting said rack and extension, all substantially as set forth.

2. A lifting jack provided with a rack in the form of a trough, a telescopic section, 45 also in the form of a trough and adapted to fit within the rack as described, each of said parts being provided with engaging devices arranged to take one into the other and to hold the parts in an extended position. 50

3. A lifting jack provided with a hollow rack combined with a hollow telescopic section, one provided with lugs and the other with apertures adapted to engage said lugs all substantially as set forth. 55

4. A lifting jack provided with a hollow rack combined with a hollow telescopic section, said section being provided with a head at the top, and apertures in its wall and said rack being provided with a top which fits the bottom of the telescopic section head, and lugs which are adapted to engage the apertures in the telescopic section, all substantially as set forth. 60

5. A lifting jack provided with a rack in 65 the form of a trough combined with a telescopic section in the form of a trough, each part provided with engaging devices arranged to take one into the other and to hold the parts in an extended position, and stops 70 adapted as described to prevent the entire separation of the parts, all substantially as set forth.

In testimony whereof, I have signed my name to this specification in the presence of 75 two subscribing witnesses, this fifteenth day of June 1904.

ANSON SEARLS.
